CLAIM

The ornamental design for a light shield of a head-mounted display, as shown and described.

DESCRIPTION

FIG. 1 is a perspective view of front, top and right side of a light shield of a head-mounted display showing a first embodiment of our new design;

FIG. 2 is a perspective view of front, bottom and right side thereof;

FIG. 3 is a perspective view of rear, top and left side thereof;

FIG. 4 is a perspective view of rear, bottom and left side thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines depict portions of the light shield of a head-mounted display that form no part of the claimed design.
